(57) **CLAIM**

The ornamental design for a display screen or portion thereof with graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen or portion thereof with graphical user interface showing our new design;

FIG. 2 is a second embodiment thereof;
FIG. 3 is a third embodiment thereof;
FIG. 4 is a fourth embodiment thereof;
FIG. 5 is a fifth embodiment thereof;
FIG. 6 is a sixth embodiment thereof;
FIG. 7 is a seventh embodiment thereof;
FIG. 8 is a eighth embodiment thereof;
FIG. 9 is a ninth embodiment thereof;
FIG. 10 is a tenth embodiment thereof;
FIG. 11 is a eleventh embodiment thereof;
FIG. 12 is a twelfth embodiment thereof;
FIG. 13 is a thirteenth embodiment thereof;
FIG. 14 is a fourteenth embodiment thereof;
FIG. 15 is a fifteenth embodiment thereof;
FIG. 16 is a sixteenth embodiment thereof;
FIG. 17 is a seventeenth embodiment thereof;
FIG. 18 is a eighteenth embodiment thereof;
FIG. 19 is a nineteenth embodiment thereof;
FIG. 20 is a twentieth embodiment thereof;
FIG. 21 is a twenty-first embodiment thereof;
FIG. 22 is a twenty-second embodiment thereof;
FIG. 23 is a twenty-third embodiment thereof;
FIG. 24 is a twenty-fourth embodiment thereof;
FIG. 25 is a twenty-fifth embodiment thereof;
FIG. 26 is a twenty-sixth embodiment thereof;
FIG. 27 is a twenty-seventh embodiment thereof;
FIG. 28 is a twenty-eighth embodiment thereof;
FIG. 29 is a twenty-ninth embodiment thereof;
FIG. 30 is a thirtieth embodiment thereof;
FIG. 31 is a thirty-first embodiment thereof;
FIG. 32 is a thirty-second embodiment thereof;
FIG. 33 is a thirty-third embodiment thereof;
FIG. 34 is a thirty-fourth embodiment thereof;
FIG. 35 is a thirty-fifth embodiment thereof;
FIG. 36 is a thirty-sixth embodiment thereof; FIG. 37 is a thirty-seventh embodiment thereof;
FIG. 38 is a thirty-eighth embodiment thereof;
FIG. 39 is a thirty-ninth embodiment thereof; and,
FIG. 40 is a fortieth embodiment thereof.

The broken lines around the Figures show a display screen or portion thereof and form no part of the claimed design. The broken lines within the Figures and the areas within the broken lines show unclaimed portions of the graphical user interface and form no part of the claimed design.
